(57) **CLAIM**

We claim the ornamental design for a computing device, as shown and described.

DESCRIPTION

FIG. 1 is a perspective view of a computing device; FIG. 2 is a top plan view thereof; FIG. 3 is an enlarged fragmentary sectional view thereof taken along lines 3-3 of FIG. 2; and FIG. 4 is an enlarged fragmentary sectional view thereof taken along lines 4-4 of FIG. 2. FIG. 5 is a perspective view of another embodiment of the computing device of FIG. 1; FIG. 6 is a top plan view of the computing device of FIG. 5; FIG. 7 is an enlarged fragmentary sectional view of the computing device of FIG. 6 taken along lines 7-7; and, FIG. 8 is an enlarged fragmentary sectional view of the computing device of FIG. 6 taken along lines 8-8. The dash-dash broken lines in the drawings are environmental lines while the short dash-long dash lines are boundary lines, neither of which are part of the claimed design.
